Primary Examiner — Stacia Cadmus(74) *Attorney, Agent, or Firm* — Marilyn Matthes Brogan; Paul A. Levy; Frommer Lawrence & Haug LLP(57) **CLAIM**

The ornamental design for a wheel rim, as shown and described.

DESCRIPTION

FIG. 1 is a perspective view of a wheel rim, showing my new design;

FIG. 2 is a front view thereof;

FIG. 3 is another perspective thereof;

FIG. 4 is a perspective view of a second embodiment of a wheel rim, showing my new design;

FIG. 5 is a front view of FIG. 4; and,

FIG. 6 is another perspective of FIG. 4.

The broken lines shown in the figures are for the purpose of illustrating structure that forms no part of the claimed design.
